SLIP LASTING LAST

Fred L. Ayers, Waltham, Mass.

Application May 17, 1944, Serial No. 535,962

1 Claim. (Cl. 12—135)

1

This invention relates to lasts for use in making shoes by the slip lasting method. In accordance with this method a shoe upper and a flexible innersole are secured together about their margins to the desired extent, after which a last is forced in between them in order to shape the shoe. After the last has been forced into place, other manufacturing operations commonly performed while the last in the shoe may be effected, and the shoe completed in any desired manner.

This invention relates to the construction of a last for facilitating the forcing of the last into position and the later removal of the last from the shoe. To these ends the last is made in a plurality of endwise sections, the end ones of which may be easily inserted into the toe and heel portions of the shoe, after which an intermediate section is forced between the end sections in a manner to wedge them apart until the intermediate section is in its final position and the end sections extended to the full normal length of the last and with the shoe stretched and properly shaped.

In order to prevent loss of any of the last sections, means may be provided for holding them at least partly assembled so that they are always in condition to be moved between a retracted position in which they may be freed from the shoe, or placed in an alined and expanded condition in which they properly support the shoe mounted thereon.

For a complete understanding of this invention reference may be had to the accompanying drawings in which

Figures 1 and 2 are side elevations of the last in extended and contracted conditions, respectively, the shoe parts being shown in dotted lines during the slip lasting operation.

Figures 3 and 4 are sectional views on lines 3—3 and 4—4, respectively, of Figure 1.

Figure 5 is a top plan view of the last in extended condition.

In the drawings, there is illustrated a last particularly suitable for accomplishing the "slip lasting" operation. As shown this last comprises a separate forepart portion 40, a heel portion 41 having a last pin socket 42 therein, and an intermediate portion 43. The confronting faces of the portions 40, 43 and 41 lie along non-parallel planes transverse to the length of the last, these planes converging toward the sole face of the last, and these confronting faces are preferably provided with mating interengaging guide members 47 and 48 shown as of dovetail cross section, which guide the portions for relative sliding mo-

tion in directions which will positively wedge the end portions 40 and 41 apart into the positions shown in Figure 1, or positively draw them together as shown in Figure 2. In order to hold the forepart portion 40 and the heel portion 41 in proper relation to each other, a pair of guide rods 44 may be fixed in one of these parts, herein shown as the part 40, extending through slots 45 through the intermediate portion 43, and into guide sockets 46 in the other end portion shown as the heel portion 41. When the parts are contracted as shown in Figure 2, the last is in condition to be slipped in between the upper materials and the flexible sole member which have been secured together to the desired extent around their margins and, which are then in the position shown in the dotted lines of Figure 2. If now the intermediate portion 43 be pressed downwardly toward the position shown in Figure 2, the forepart and heel portions are forced apart, the forepart portion of the last being forced into the toe portion of the shoe, and the heel portion into the heel end of the shoe, filling out the space between the flexible sole member and the upper materials and causing the shoe to be shaped to the last.

It is desirable that means be provided for retaining the last in its extended position, and to this end, a spring latch pin 50 is shown which is seated in a socket 51 in the intermediate last portion 43 and is adapted to snap into an open ended socket 53, which is preferably in the forepart section 40 of the last near its upper end where it is accessible to release the latch when the shoe is on the last and is laced up. Thus when the intermediate portion 43 is pushed into its wedging position of Figure 1, the latch 50 snaps into the socket 53 and holds the last parts extended. The last may be released by inserting a rod, shown in dotted lines at 54 in Figure 1, into the latch socket 53, retracting the latch so as to release the portions 40 and 43 for sliding motion to contract the length of the last. A screw eye 56 carried by the wedge portion 43 may receive a tool for retracting this portion to the position of Figure 2. Ordinarily it will not be found necessary to latch the intermediate portion 43 to the heel portion 41, but of course this may be done, if desired.

From the foregoing description of an embodiment of this invention, it should be evident to those skilled in the art that changes and modifications might be made without departing from the spirit or scope of this invention.

2

I claim:

A last having end portions comprising a forepart and a heel portion, a wedge shaped intermediate portion, said portions having cooperating dovetail guides on the adjacent faces of said portions causing sliding of said intermediate portion in wedging and relieving directions to extend or retract said forepart and heel portions, said intermediate portion having spaced slots therethrough, a guide bar extending through each of said slots and secured at one end to one of said end portions and slidably guided in the other of said end portions, and means for latching said intermediate portion to one of the other portions.
